UNITED STATES PATENT OFFICE.

LEO HARRIS, OF LANCASTER, CALIFORNIA.

FOLDING-BED ATTACHMENT FOR AUTOMOBILES.

1,274,539.

Specification of Letters Patent. Patented Aug. 6, 1918.

Application filed July 30, 1917. Serial No. 183,593.

To all whom it may concern:

Be it known that I, LEO HARRIS, a citizen of the United States, residing at Lancaster, in the county of Los Angeles and State of California, have invented new and useful Improvements in Folding-Bed Attachments for Automobiles, of which the following is a specification.

My object is to make an improved folding bed attachment for automobiles which may readily be rigidly connected, which may be unfolded and made up to form a good substantial bed, which will carry its own tent cover, and which may readily be folded into a compact form to ride behind the automobile.

In the drawings;

Figure 1 is a perspective of my folding bed attachment for automobiles made up, covered, and ready for use, the forward part of the automobile being broken away.

Fig. 2 is an enlarged side elevation of the frame with the cover and bedding removed, and showing the folded positions in dotted lines.

Fig. 3 is a fragmentary plan.

Fig. 4 is a cross-section on the line 4—4 of Fig. 2.

Two attaching and supporting bars 1 are rigidly connected by a head rail 2. The forward ends 3 of the bars 1 are adapted for attachment to the rear end of the body 4 of the automobile and, of course, these forms of attachment will be varied for different automobiles and for attachment in different places upon the automobiles. In the form shown, bolts 5 are inserted horizontally through the bars 1 and pass through the sills 6 of the car body and form a rigid connection so that said bars 1 will extend horizontally backwardly beyond the rear seat. The head rail 2 is perforated to receive the helicals 7 for supporting the forward end of the fabric 8. The folding side bars 9 are hinged to the rear ends of the bars 1 by bolts 10. The second folding side bars 11 are hinged to the rear ends of the side bars 9 by the bolts 12, and the third folding side bars 13 are hinged to the rear ends of the bars 11 by bolts 14. The rear ends of the bars 13 are connected by the foot rail 15 having perforations to receive the helicals 16 for supporting the rear end of the fabric 8. Posts 17 extend downwardly from each end of each of the bars 11 and the lower ends of the posts 17 are connected by the longitudi-

nal bars 18 and the transverse bars 19 so as to form a rigid box frame, the bars 19 being low enough to allow the fabric 8 to sag under the load without striking the bars. 60 Folding legs 20 are connected to the ends of the bars 19 by bolts or rivets 21 so that the legs may swing inwardly and upwardly beside the bars 19 and swing downwardly to vertical positions to support the box 65 frame. Legs 22 are connected to the ends of the foot rail 15 by bolts or rivets 23 so that the legs may swing upwardly beside the foot rail and swing downwardly to vertical positions and support the foot rail 15. 70 Swiveled eye-bolts 24 and 25 are inserted through the head rail 2 and foot rail 15 at their transverse centers and telescoping tent poles or cover supports 26 and 27 are mounted 75 through the eyes of these bolts. Each pole or support is preferably formed in three pieces, 28, 29 and 30, said pieces being formed of pipe. A ring 31 is fixed upon the upper end of the piece 28. The piece 29 telescopes through the ring 31 into the piece 28 and is held in adjusted position by a set-screw 32. A similar smaller ring 33 is fixed upon the upper end of the piece 29 and the piece 30 telescopes through this ring into 80 the piece 29 and is held in adjusted position by a set-screw 34. A cap or head 35 is fixed upon the upper end of the piece 30. When the set-screws are loosened and the pieces are shoved together, the piece 28 may be 85 manipulated through the eye-bolt to bring the eye-bolt approximately at the center and then the collapsed pole may be swung into horizontal folded position beside the head rail or foot rail, as shown in dotted lines in 90 Fig. 3. Headed studs are fixed in the bars 1, 9, 11, 13 and 15 to form outwardly projecting buttons 36. A hook 37 is adapted to engage the rear bow 38 of the automobile top and a cord 39 is attached to this hook 100 and extends over the tops of the extended poles 26 and 27 and then downwardly and outwardly to the tent stake 40. The canvas cover 41 is made up like an A-tent and the cord 39 has sockets 42 at the ends of the ridge to engage the caps 35 upon the poles 26 and 27. The cover is placed in position so that the portion of the cord 39 between the sockets 42 forms a ridge pole and the lower edges of the canvas are provided with 105 button-holes 43 to engage the buttons 36 all the way around or to any desired extent. 110

Screen windows 44 may be made of mosquito netting or screen and inserted in the lower parts of the ends of the cover and in the upper parts of the sides to ventilate the 5 interior and keep out flies and mosquitos. The cover 41 is preferably constructed in two sections meeting and overlapping transversely at or near the longitudinal center of the bed, and the overlapping flaps 45 and 10 46 may be secured together by interior buttons 47. These flaps and buttons may be arranged in various ways to suit the convenience of the occupant.

After the bed frame has been properly installed upon the car and it is desired to fold up the bed and get ready for the road, the poles 26 and 27 are collapsed and folded against the rails 2 and 15, the rail 15 is swung upwardly, the legs 22 folded, then 20 the continued swinging over of the foot rail 15 will swing the bars 11 upwardly until the bars 13 are parallel with the bars 9. Then the box frame is swung upwardly until the bars 9 are in vertical positions, 25 thus bringing the bars 13 close to the rear face of the rear seat with the box frame extending upwardly back of the lower part of the car top. The cover 41 and the bedding may be left upon the fabric 8 and 30 rolled up with the frame. Latches 48 are pivoted to the bars 1 and have notches 49 to engage buttons 36 upon the bars 9 so as to hold the bed in its folded position, as shown in dotted lines in Fig. 2.

35 When it is desired to make up the bed, the latches 48 are disconnected and the frame unfolded backwardly, the bedding piled upon the fabric 8, the poles 26 and 27 extended to the desired height, the cover 41 40 applied, the hook 37 engaged with the bow 38, the cord 39 drawn tight, and the stake 40 driven into the ground. The cover may be buttoned to the frame more or less as desired.

45 It is obvious that by making the cover tight to fit the frame and buttoning it all the way around, it is perfectly practical to exclude all forms of insects from the interior of the cover.

50 I claim:

1. A folding bed attachment for automo-

biles, comprising supporting and attaching bars adapted to be rigidly secured to the automobile and extend horizontally for supporting the entire folded bed and for supporting one end of the unfolded bed, a head rail rigidly connecting the supporting and attaching bars, folding side bars hinged to the extending ends of the supporting and attaching bars, a box frame hinged to the rear 55 ends of the folding side bars, folding legs for supporting the box frame, an end frame hinged to the opposite side of the box frame from the side bars, and folding legs for supporting the end frame; so that the end 60 frame will swing upwardly and then swing forwardly and the box frame will swing upwardly and then the folding side bars will swing upwardly carrying the box frame to a bottom-up position above the supporting 65 and attaching bars.

2. A folding bed attachment for automobiles, comprising supporting and attaching bars adapted to be rigidly secured to the automobile and extend horizontally for supporting the entire folded bed and for supporting one end of the unfolded bed, a head rail rigidly connecting the supporting and attaching bars, folding side bars hinged to the extending ends of the supporting and attaching bars, a box frame hinged to the rear 70 ends of the folding side bars; said box frame comprising second folding side bars, posts extending downwardly from each end 75 of each of the second folding side bars, longitudinal bars connecting the lower ends of the posts, and transverse bars connecting the lower ends of the posts so as to form a rigid box frame; folding legs for supporting 80 the box frame, an end frame hinged to the opposite side of the box frame from the side bars, and folding legs for supporting the end frame; so that the end frame will swing upwardly and then swing forwardly and the box frame will swing upwardly and then 85 the folding side bars will swing upwardly carrying the box frame to a bottom-up position above the supporting and attaching bars.

In testimony whereof I have signed my 90 name to this specification.

LEO HARRIS.
